UNITED STATES PATENT OFFICE.

HERBERT A. STREETER, OF CHICAGO, ILLINOIS.

MEANS FOR CLAMPING AND SECURING CROSS METAL BEAMS TOGETHER.

SPECIFICATION forming part of Letters Patent No. 729,445, dated May 26, 1903.

Application filed February 13, 1903. Serial No. 143,190. (No model.)

To all whom it may concern:

Be it known that I, HERBERT A. STREETER, a citizen of the United States, residing in Chicago, in the county of Cook and State of Illinois, have invented a new and useful Improvement 5 in Means for Clamping and Securing Cross Metal Beams Together, of which the following is a specification.

My invention relates to improvements in 10 means for securing and clamping together crossing metal beams in roofs and other structures.

The object of my invention is to provide a 15 simple and economical means for securing and spacing on the rafters or slanting beams of the roof the customary metal cross beams or bars.

My invention consists in the novel construction of parts and devices and in the novel combinations of parts and devices herein shown or described.

In the accompanying drawings, forming a 20 part of this specification, and in which like letters of reference indicate like parts, Figure 1 is a plan view of a device embodying my invention. Fig. 2 is a side elevation. Fig. 3 is a section on line 3 3 of Fig. 1. Fig. 4 is a section on the line 4 4 of Fig. 1. Fig. 5 is a plan view showing a modified construction 25 of the clips or clamping and securing devices. Fig. 6 is an elevation of the construction shown in Fig. 5. Fig. 7 is a section on the line 7 7 of Fig. 5. Figs. 8, 9, 10, 11, and 12 show constructions where one of the clips 30 or securing devices is omitted.

In the drawings, A represents the longitudinal steel beams or rafters of the roof, and B the cross beams or bars. The cross beams or bars B are secured to the rafters or incline- 35 beams A at each crossing of the beams by means of a pair of metal clips or securing devices D and F.

The longitudinal beams or rafters A may 40 preferably be I-beams, and the cross-beams B angle beams or bars. The clip or securing device D comprises an upright or edgewise-fitting plate d, having a foot portion d', fitting on the top face of the beam A, and a notched portion d² on the flange b of angle- 45 beam B, a pair of clamps d³, each having a bend or hook d⁴ to embrace the upper flange of beam A and an upright flange d⁵, and a

clamp-bolt d⁶, which passes through the upright flanges d⁵ of the clamps d³ and the upright or edgewise-fitting piece d. By screwing up the nuts d⁷ d⁸ of the clamp-bolt the clamp-pieces d³ are caused to firmly embrace or clamp the rafter or incline-beam A with a secure grip, and thus prevent the cross or angle beams B from slipping down. The edge 55 of the flange b of the angle-beam B abuts directly against the edges of the pair of clamp-pieces d³. The clip or securing device F comprises an upright member f, having a bend or hook f', adapted to fit over and embrace 60 the upright flange b' of the cross or angle beam B and provided with a right-angle twist f² to bring its lower portion transverse to said hook f', and a pair of clamps f³, each having a bend or hook f⁴ to embrace the edge 65 of the upper flange of the beam A and an upright flange or portion f⁵, and a clamp-bolt f⁶, which passes through the upright flanges f⁵ and the lower part f⁷ of the upright member f. The clamp members f³ are similar in 70 construction and operation to the clamp-pieces d³ and serve to firmly clamp or grip the upper flange a of the beam A. The clamp-bolt f⁶ is provided with nuts f⁸ f⁹.

In the modified construction illustrated in 75 Figs. 5, 6, and 7 the upright or edgewise-fitting member d, which fits on the foot or flange b of the angle beam or bar B, is duplicated. Each of the duplicate upright or edgewise-fitting pieces d is made integral 80 with one of the clamp-pieces d³, and in this modified construction shown in Figs. 5, 6, and 7 the clamp-pieces f³ are made integral 85 with the upright member f, which hooks over the upright flange b' of the angle-beam, and the clamp-bolt f⁶ is in this construction omitted. In this modified construction one of the hooks or bends f⁴ is formed after the clip is applied to the crossing beams A B. 90

In Fig. 11 I have illustrated the preferred, 95 stronger, and perfected construction of the upright or edgewise-fitting piece d, the same having an extension d⁹ to fit against the upright web or flange b' of the beam B and having its foot d' furnished with an extension d¹⁰ 100 to give a more extended bearing upon the beam A and its notched portion d², which fits on the flange b of the beam B, also furnished with an extension d¹¹ to give a more extended

bearing on said flange *b*. By this construction of the upright or edgewise-fitting piece *d* the beam *B* may be very firmly secured in place by the clip or securing device *D* alone 5 on one side.

In the construction illustrated in Figs. 8, 9, and 10 the upright or edgewise-fitting piece *d* is provided with an extended foot *d⁹* and the extended notched portion *d¹⁰*, but without the 10 extension *d⁸* that fits against the upright web or flange *b'* of the beam *B*.

In the modification shown in Fig. 12 one of the upright flanges *d⁵* is furnished with a threaded hole to receive the clamp-bolt *d⁶*, 15 and one of the nuts of the bolt is omitted.

I claim—

1. The combination with crossing beams or bars *A B*, of a clip or securing device *D* having an upright or edgewise-fitting notched piece 20 *d*, a pair of clamp-pieces *d³*, a clamp-bolt *d⁶*, and a clip or securing device *F* having an upright member *f* furnished with a hook *f'*, a twisted portion *f²* and a pair of clamps *f³* and clamp-bolt *f⁶*, substantially as specified.

25 2. The combination with a pair of crossing beams or bars, of a clip or securing device *D* having an upright or edgewise-fitting member *d*, clamp-pieces *d³*, a clamp-bolt *d⁶*, and a clip or securing device *F* having a hook or 30 bend *f'* and clamp-pieces *f³ f³*, substantially as specified.

3. The combination with a pair of crossing beams or bars *A B*, of a clip or securing device having an edgewise-fitting piece or member *d* provided with a notched extension *d¹⁰* 35 and an upright extension *d⁸* fitting against the upright web or flange of the beam or bar *B*, and an extension *d⁹* fitting against the upper face of the beam *A*, and clamps *d³* and 40 clamp-bolt *d⁶*, substantially as specified.

4. The combination with a pair of crossing beams *A B*, of a clip or securing device *D* having an extended notched portion *d¹⁰* and an extended foot portion *d⁹*, a pair of clamps *d³* embracing the upper flange of beam *A*, and a clamp-bolt *d⁶*. 45

5. The combination with a pair of crossing beams or bars, of a clip or securing device having a pair of clamps embracing the upper flange of the lower beam and each furnished 50 with an upright flange, a clamp-bolt extending through said flanges, and provided also with a member engaging one of the flanges of the upper beam, substantially as specified.

6. The combination with a pair of crossing beams or bars, of a clip or securing device having a pair of clamps embracing the upper flange of the lower beam and each furnished 55 with an upright flange, a clamp-bolt extending through said flanges, and provided also 60 with a member engaging one of the flanges of the upper beam, said member which engages the flange of the upper beam having also a foot portion resting on the lower beam, 65 substantially as specified.

7. The combination with a pair of crossing beams or bars, of a clip or securing device having an upright member provided with a hook or bend, and a pair of clamps to embrace the flange of the lower beam, substantially as specified. 70

8. The combination with a pair of crossing beams or bars, of a clip or securing device *F* having an upright member *f* furnished with a hook *f'*, a twisted portion *f²*, and a pair of 75 clamps *f³*, substantially as specified.

HERBERT A. STREETER.
